CLAIM

The ornamental design for a toilet sanitizing seat and lid, as shown and described.

DESCRIPTION

FIG. 1 is a top perspective view of the toilet sanitizing seat and lid of the invention with the lid closed, the toilet seat mounted on a toilet that is shown in dashed lines as not forming a part of the invention.

FIG. 2 is a top perspective view of the toilet sanitizing seat and lid of FIG. 1 shown with the lid open.

FIG. 3 is a top plan view of the toilet sanitizing seat and lid of FIG. 1.

FIG. 4 is a bottom plan view thereof.

FIG. 5 is a front elevation view thereof; and,

FIG. 6 is a right side view thereof, the left side being a mirror image.
